UNITED STATES PATENT OFFICE.

HERBERT BROWN, OF BELFAST, IRELAND.

ELECTRIC SIGNALING ON RAILWAYS.

1,072,567.

Specification of Letters Patent. Patented Sept. 9, 1913.

Application filed December 29, 1911. Serial No. 668,430.

To all whom it may concern:

Be it known that I, HERBERT BROWN, a subject of the King of Great Britain and Ireland, and residing at 14 Dublin road, 5 Belfast, Ireland, have invented certain new and useful Improvements in and Relating to Electric Signaling on Railways, of which the following is a specification.

The present invention relates to electric 10 signaling on railways and particularly to signaling systems of the type in which signals are given in the cab of a locomotive.

The object of the invention is primarily to extend the scope and usefulness of the 15 system described in the specification of British Patent No. 18,996 of 1908; though as will be indicated hereinafter, the use of the present invention is not restricted to the system referred to.

20 To this end the invention consists in an electric signaling system for railways according to which circuits corresponding to different types or classes of signal are defined or selected on the locomotive or other 25 vehicle by the operation in suitable combinations of a series of track selectors.

By the words type or class of signal, I mean for example a home signal apart from 30 whether it stands at danger or clear, or again a route indicator quite apart from the route shown.

According to the preferred form of my 35 invention the signal last given on the locomotive is maintained until the next signaling point is reached, the condition or state of any type of signal selected being determined either by hand or automatically by help of suitable track circuits.

40 A further part of the invention thus consists in a system of signaling as indicated with means for maintaining on the locomotive or the like the signal last given.

The invention also consists in the signaling systems and certain details or adjuncts 45 thereof to be hereinafter described.

Referring now to the accompanying drawings which illustrate my invention and form part of my specification: Figure 1 shows a side elevation of a collecting shoe. Fig. 2 50 shows an end elevation of same, while Fig. 3 shows a cross section on the line A—A Fig. 1. Fig. 4 shows one arrangement of track circuits and ramp rails for giving stop signals.

Fig. 5 shows one arrangement of track circuits and ramp rails for giving repeater signals. Fig. 6 shows one arrangement of

track circuits and ramp rails for giving distant signals. Fig. 7 shows one arrangement of track circuits and ramp rails for giving stop and distant signals together. Fig. 8 60 shows one method of arranging the signaling circuits in the locomotive according to my invention.

In carrying my invention into effect according to one form I provide collecting 65 shoes on each side of the locomotive. One arrangement of collecting shoes is illustrated in Figs. 1 to 3. In these figures a plate, *a*, is attached directly to the horn plates by studs, *b*, and is also connected thereto by 70 means of brackets, *c* and *d*. Lugs, *e* and *f*, are formed on the plate, *a*, and coöperate with brackets, *g* and *h*, riveted thereto to form bearings for the pins, *i* and *j*, supporting slotted links, *k* and *l*. These links 75 are attached to a carriage by pins, *n* and *o*, respectively, the carriage being formed of plates, *p* and *q*, held apart from one another by distance pieces, *r*. On the carriage, *m*, three pairs of collecting shoes, *A*₁, *A*₂ and 80 *A*₃, of oval cross section at their contact ends are disposed, the members of each pair being arranged to contact with the same ramp and connected in parallel with one another. The shoes, *A*₁ and *A*₃, are slidably 85 mounted upon brackets, *s* and *t*, which are attached securely to the carriage. Rods, *u* and *v*, are mounted upon the shoes *A*₁ and *A*₃, and carry springs, *w* and *x*, which serve to keep the shoes pressed against the ramp 90 rails. The brackets, *s*, and *t*, are suitably insulated from the carriage and from their connecting rivets as for example by the insertion of suitably shaped pieces of mica. A number of distance pieces, *y*, are disposed 95 between the head of the shoes and the opposing face of the brackets, *s* and *t*, for adjustment purposes.

The shoes, *A*₂, are disposed between the plates, *p*, and *q*, and are attached to box-shaped sleeves, *z*, which may be insulated from the shoes by similarly shaped mica pieces, *14*. Studs, *15*, are connected to the top of the shoes, *A*₂, and form a guide for one end of springs, *16*, the other ends of 100 which are mounted on a similar stud, *17*, attached to a bridge piece, *18*. The bridge piece, *18*, spans the plates, *p* and *q*, being attached thereto by cotter bolts, *19*.

105 It will be seen from the above description 110 that all the shoes are resiliently mounted on the carriage in such a manner as to enable

them to be pressed against the ramp rails and make electrical contact therewith as the locomotive travels along the track.

As it may happen that obstructions may be encountered by the shoes it is advisable to provide suitable arrangements for allowing the whole carriage to be raised to clear the obstruction.

In the arrangement illustrated a spring, 20, is carried by plate, 21, secured to the bridge piece, 18, a screwed pin, 22, being provided for retaining the spring in position. The ends of the spring slide upon plates, 23 and 24, attached to the plate, *a*.

By means of the slotted links, *k* and *l*, in the event of an obstruction being encountered, the carriage is enabled to rise a considerable distance in order to clear the obstruction and is thereafter returned to its normal position by the spring, 20.

By arranging the collecting shoes in the manner described, *i. e.* so that a pair of shoes contacts with each ramp rail, it is found that efficient contact between the shoes and the ramp rail may be made when the locomotive is traveling at very high speeds.

The raising of some or all of the shoes causes circuits to be completed on the locomotive either by contacts which co-act with the shoe rods as shown diagrammatically in Fig. 8, or by arranging that the motion of the shoes or their rods actuates the lever arms, 86, Fig. 3, attached to cylinders, 87, upon which suitable contacts are disposed. The actuation of the lever arm, 86, rotates the cylinder and closes circuits between contact fingers, 88, thus completing circuits on the locomotive either directly or indirectly by means of relays.

The type of signal is differentiated by the number and grouping of the ramp rails on the track, which act upon certain of the shoes on the locomotive and lift them upward with respect to the carriage and operate switches for defining the type and position of the signal.

In Figs. 4 to 7 I have illustrated arrangements of ramp rails and track circuits for operating "stop" "repeater" "distant" and simultaneous "stop" and "distant" signals, as well as giving route indications.

In Fig. 4 the ramp rails and track circuits for giving "stop" signals are represented. The ramp rails are formed of three angle bars placed at one side of the track, both ends of the bars being inclined in the usual manner. A switch, 32, controls the track circuit connecting the ramp rails, 28 and 26, while a second switch, 33, controls a track circuit arranged in parallel with the first circuit between ramp rails, 28 and 27. The position of the switches, 32 and 33, determines the nature of "stop" and "route" signals displayed on the locomotive when passing over the ramp.

The "route" signal which I use throughout my system serves merely as an indication to the driver of the general state of the line upon which the locomotive is about to travel. For example, if the line contains sharp curves or junctions, the signal "slow road" will be given but if free from curves or junctions the signal "fast road" will be given.

In Fig. 5 the ramp rails and their co-operating circuits are shown for giving "repeater" signals. In this case three ramp rails 26, 27 and 28 are arranged on one side of the track and a single ramp rail, 30, on the other, the ramp rail 30 being connected permanently in parallel with ramp rail, 27. The connection of ramp rails, 30 and 27, in parallel facilitates the collection of the current. The positions of the switch, 32, which controls the track circuits, interconnecting ramps 28, 27 and 30, and the switch, 33, which controls the track circuits interconnecting ramps, 28 and 26, determines the nature of the signals displayed when the locomotive reaches the ramp rails.

The "repeater" signal ramp rails are placed at such a distance in the rear of the "stop" signal ramp rails as will enable the locomotive to be conveniently brought to a standstill on the latter rails if necessary. The "repeater" signal is intended as a warning or an indication in advance of the signal to be expected on arriving at the "stop" signal rails. Upon receiving the "repeater" danger signal which is distinct from "stop" and "distant" danger signals the driver must be prepared to pull up upon the "stop" signal ramp rails so that if the danger signal is displayed on arriving at the ramp rails the locomotive may remain thereon until the "clear" signal is indicated. If the "clear" signal is received on the repeater ramp rails then this indicates that a clear signal will be given under normal circumstances when the stop signal rails are reached.

For indicating "distant" signals I arrange the ramp rails and the track circuits as shown in Fig. 6. In this case, six ramp rails are used, three on each side of the track. The rail, 26, is connected to rail, 28, and the rail, 27, to 28, by switches, 32 and 33, while the rails, 29, 30 and 31, are connected permanently in parallel with rails, 26, 27 and 28, respectively.

The positions of the switches, 32, and 33, determine the nature of the "route" and "distant" signals displayed on the locomotive.

In Fig. 7 an arrangement for giving "stop" and "distant" signals simultaneously is shown. Three ramp rails, 26, 27 and 28, are arranged on one side of the track and two ramp rails, 29 and 31, arranged on the other. The ramp rails, 26 and 28, are

connected through a switch, 32, and the rail, 27, is connected through a switch, 33^a, to the ramp rail, 31. The switch, 35, connects ramp rails, 29 and 31. The nature of the 5 "stop," "distant" and "route" signals displayed on the locomotive are determined by the position of the switches.

The switches, 32, 33, 33^a and 35, are arranged as shown so that in their open position 10 they connect the corresponding ramp rails to earth. The switches are disposed in the signal cabin and may be operated either by levers of the usual type or automatically by the trains themselves, so as to render signals 15 visible on the locomotive by means of the arrangement which I have illustrated in Fig. 8, and which I will now proceed to describe. In the above figure, the current which flows through the track circuits is 20 conveyed to the same by the shoes which contact with the ramp rails, 28 and 31. It will thus be seen that in the "stop" and "repeater" signal arrangements illustrated in 25 Figs. 4 and 5, the circuit controlled by the switch 33, is dependent for its energization on the closure of the switch 32. As the "fast road" signal is displayed on the locomotive by closing the switch, 33, as will be hereinafter explained, and the "danger" 30 stop" signal by opening the switch, 32, it will be impossible to display the "fast road" and "stop" or "repeater danger" signals simultaneously. The "fast road" signal can thus only be given with "clear" "stop" or 35 "repeater" signals. In Figs. 6 and 7, however, the switches, 33 and 33^a, control the "route" signals, and as they are directly connected to the ramps, 28 and 31, in their respective arrangements, it will be evident 40 that the "fast road" signal may be displayed independently of the danger "distant" or "stop" signals. In this arrangement the "clear" and "fast road" signals are dependent upon the closure of the appropriate 45 switches and track circuits for their indication on the locomotive; certain other signals however, such as the "danger" and "slow road" signals are independent of the closure of the track circuits and are displayed 50 upon the locomotive whenever the collecting shoes contact with the ramp rails. Failure to close the track circuits interconnecting the members of a set of ramp rails will thus result in rendering visible a danger 55 signal of the type which corresponds to the arrangement of the rails in contact with the collecting shoes.

In Fig. 8, which illustrates one method of arranging the locomotive circuits only one 60 set of collecting shoes on each side of the locomotive is represented in order to avoid complexity in the drawings but as the members of each pair of shoes are connected in parallel with the track and locomotive circuits 65 the raising or lowering of one or both

members of the pair produces the same effect on the locomotive circuits.

The signals are arranged within a casing, 25, the front of which is provided with obscured glass so that only the illuminated signals are visible. Behind the obscured glass a metal plate is provided with windows fitted to represent the signals illustrated in the figure, the windows being provided with glass colored to correspond with the signal given. Behind each window is a light-tight compartment fitted preferably with two lamps arranged in parallel so that if one of the lamps fails the second lamp may still be able to illuminate the signals. 70 The above arrangement prevents any other signal than the operative ones being disclosed. 75

The power for lighting the lamps may be provided by a storage battery, 36, carried 80 on the locomotive, the wires of the lighting circuits on Fig. 8 being represented by thin black lines.

The lighting circuits are controlled by solenoids M, R, M S, H, D, S S, the solenoids being controlled by the position of the shoes and by relays, A R, and B R, operating in conjunction therewith, and also by the track circuits. 90

The solenoids are disposed on the locomotive so that the cores thereof which operate a series of contacts situated above and below the solenoids, normally close the contacts situated on the under side of the solenoid, but when the solenoids are energized, 95 the cores are raised against the action of gravity and close the contacts on the upper sides of the solenoids. 100

The solenoid R controls the route indicator and is energized on the closure of the 105 appropriate track circuits by switch, 33.

The relays, A R and B R, are energized by the raising of the collecting shoes, A₂ and B₂, respectively while the solenoid, S S, is energized by the raising of the shoes, A₃ and B₃, simultaneously. The relays A R and B R, as well as the solenoid, S S, are independent of the track circuits as regards their energization, as the circuits controlling them are carried wholly on the locomotive. 110 These circuits are normally open as hereinafter described and are closed on the corresponding collecting shoes being raised on encountering the ramp rails. 115

The energization of the solenoid, M S, 120 is dependent upon the energization of both relays, A R, and B R, while the energization of the solenoids, H or D, is dependent upon the closure of appropriate track circuits through switches, 32 and 35, and the 125 energization of either of the relays, A R or B R.

The power for operating the solenoids is supplied by a dynamo, 38, carried by the locomotive the positive lead of which is 130

represented on the drawings by a thick continuous line, while the return lead is represented by a dotted line.

As it is advisable to retain the last signal indicated on the locomotive between sets of ramp rails, I provide means for effecting this result. The controlling device for this purpose is the solenoid M, and the leads therefrom to the other solenoids are represented by chain dotted lines, m a, m b, m c, m d, and m e.

Collecting shoes, A₁, A₂, A₃, and B₁, B₂ and B₃, are adapted to be raised by arrangements of ramp rails such as I have before described, the number and arrangement of rails determining the type of signal to be given. Coöperating with the spindles of the collecting shoes are a series of studs, 39 to 44, which act in conjunction with contacts, 45 to 50, to close a supplementary set of circuits in the manner hereinafter described.

The leads from the various devices are attached to terminals, 1 to 12. The terminal, 1, is adapted to carry the return wire, 1^a, from the various solenoids back to the dynamo. The lead, 2^a, through the terminal, 2, is the positive wire from the dynamo while that through the terminal, 3, is the positive, 3^a, from the storage battery to the various lighting circuits. The lead, 4^a, through the terminal, 4, passes to the "out of action" signal which is automatically displayed in special circumstances as for example when the ramp rails are accidentally earthed from any cause. The lead, 5^a, is earthed through the coil, 85, of an auto-switch, 37, and passes through the terminal, 5, to the coil, P, the arrangement being such that on substantial leakage taking place, as for example when the ramp rails become earthed, the coil, P, is first of all energized and breaks the circuit through the solenoids H and D, by way of relays A R and B R. As the solenoids, H and D, control, the home and distant signals, on becoming deenergized the danger signal is automatically shown. If the leakage exceeds a certain amount the auto-switch coil, 85, is sufficiently energized to break the circuit through the dynamo, 38. Simultaneously the lighting circuit through the lead, 4^a, is completed through the contacts, 51, and the signal giving "out of action" is displayed. The terminal, 6, carries the wire, 6^a, leading from the shoe, A₁, through the contacts, p', co-acting with the coil, P, to contacts a r³ and b r³ of the relays A R and B R. The wire, 7^a, through the terminal, 7, leads from the positive pole of the dynamo through the stud, 39, and contacts, 45, when the shoe, A₂, is lifted by the ramp rail, to the solenoid of relay, A R. Through the terminal, 8, wires, 8^a and 8^b, leading from the collector shoes, A₂ and B₂, to the solenoid R, pass; this solenoid gives route indications

such as "slow road" or "fast road". The wire, 9^a, through the terminal, 9, leads from the solenoid, S S, through contacts, 50, stud, 44, lead, 70, contacts, 47, and stud, 41, to the positive lead from the dynamo, 38, when both shoes, A₃ and B₃, are raised by ramps. The wire, 10^a, through the terminal, 10, leads from the coil, M, through contacts, 49, stud, 43, lead, 60, contacts, 46, stud, 40, to the positive pole of the dynamo, 38, when collecting shoes, A₂ and B₂, are in their lowered position. The wire, 11^a, through terminal, 11, leads when the shoe, B₂, is raised by a ramp rail from the relay B R, through contacts, 48, stud, 42, to the positive lead from the dynamo. The wire, 12^a, through the terminal, 12, leads from shoe, B₁, through contacts, p², coöperating with the coil, P, to the contacts, a r⁵, and b r³, of relays A R, and B R.

The signals which the system illustrated is designed to transmit are indicated on the signal board, 25, and are as follows: First, a "ramp" signal adapted to indicate whether or not the collecting shoes on the locomotive are in contact with a set of ramp rails. Second, a "route" signal adapted to indicate whether the block upon which the train is entering is a "fast" or "slow" road. Third, a "stop" signal showing a red horizontal signal when at danger and a green inclined signal when at clear. Fourth, a "distant" signal showing a yellow horizontal forked signal when at danger and a forked inclined green signal when at clear. Fifth, a combination signal showing the "stop" and "distant" signals above described simultaneously. Sixth, a "repeater" signal showing a yellow horizontal signal when at danger and a green inclined signal when clear. Seventh, an "out of action" signal indicating that the auto-switch has opened the dynamo circuit owing to the same becoming earthed.

The arrangement of the circuits is such that if while the locomotive is passing over an arrangement of ramp rails as shown in Fig. 4, and one of the active solenoids failed, the "stop danger" signal, instead of the "stop clear" signal would be given. This result is effected by arranging that the solenoids are gravity controlled, so that on failure to become energized, or on failure occurring while energized, the falling of the solenoid core under gravity automatically gives the danger signal. As a clear "stop" signal cannot be given without energizing the solenoid H and a clear "distant" or "repeater" signal cannot be given without energizing the solenoid D, it will be obvious that the failure of either of these solenoids could not result in a "clear" signal being displayed. The energization of these solenoids is therefore necessary to give and hold the "clear" signal. Similarly a "fast

road" signal could not be given on failure of the solenoid R.

Failure of any of the other solenoids which co-act with the above could not lead in any circumstances to a signal being displayed demanding an increase of speed or less caution than the signal for which the circuits were set.

I will now describe the operation of the signals as the locomotive passes over the arrangement of ramp rails which I have illustrated in Figs. 4 to 7.

Stop signal.

15 Suppose that the locomotive is passing over the "stop" signal ramp rails illustrated in Fig. 4. The three shoes A_1 , A_2 and A_3 , would be raised and if the signalman had previously closed the switches, 32 and 33, the following operations would result:

20 *Track circuits closed.*—Current from the dynamo, 38, would pass through switch, 37, along leads, 2^a and 2^b , to the collecting shoe, A_3 , thence through the track circuits closed

25 by the switches, 33 and 32, to the shoes A_2 and A_1 . The raising of the shoe, A_2 , causes current from the lead, 2^b , to pass across contacts, 45, and stud, 39, to the lead, 7^a , thence through the terminal 7, to the solenoid,

30 A_R which it energizes thereafter returning to the negative pole of the dynamo by the lead, 1^a . The contact of the shoe, A_1 , with the ramp rail, 26, allows current from the shoe, A_3 , to pass through the track cir-

35 cuits the shoe A_1 and then by way of the lead, 6^a , terminal, 6, contacts, p' , to the contact, $a\ r^3$. As the relay, A_R , has previously been energized its core has been raised the current being thereby permitted to pass

40 across contacts, $a\ r^3$, to the leads, 52, 53 and 54, thence through contacts, $b\ r'$, lead, 55, to the contacts, h^2 , energizing the solenoid, H, and returning to the negative pole of the dynamo by wire, 1^a . From the shoe,

45 A_2 , the current passes along lead, 8^a , through terminal, 8, energizes the solenoid, R, and then passes to the return wire, 1^a . The lifting of the three shoes, A_1 , A_2 and A_3 , thus results in the energization of the solenoids,

50 A_R , H and R. As A_R serves merely as a relay the signals illuminated depend in this case upon lighting circuits closed by solenoids, H and R. The energization of the coil, H, causes a circuit to be completed be-

55 tween the contacts, h^4 , and consequently current from the lighting lead, 3^a , passes along wires, 3^b and 3^h , across contacts, $m\ s'$, along leads, 56 and 57, through contacts, h^4 , lead, 58, to the lamps which render visible

60 the clear signal G. S.

In the case of the solenoid, R, the contacts, r^4 , will be closed, the lead, 80, from the left hand contact passing to the signal

"fast road", while that on the right leads

65 by wires, 3^g , 3^b and 3^a , to one pole of the

storage battery. The return wires from the signal board may be connected either directly to the other pole of the battery or indirectly through the locomotive by a common lead x . The signal "fast road" will thus be displayed on the signal board, it being understood that on the energization of the solenoid, R, the circuit through the contacts, r' , controlling the "slow road" signal lighting circuit has been broken.

The solenoid, M, was de-energized in a manner hereafter described, when the ramp rails were encountered and the lighting current passing along lead, 3^t , through the contacts, m' , and lead, 59, illuminates the lamps of "on ramp" signal. The return wires from the "ramp" and "stop signal" lamps as well as the other signal lamps are arranged as previously indicated when describing the lighting circuits controlled by the solenoid, R. The "on ramp", "fast road" and "clear" signals are illuminated by the above arrangement so long as the locomotive is traveling over the ramp rails.

As has been already pointed out, it is advisable to retain between sets of ramp rails, the "road" and "signal" indications last received, the coil, M, becomes operative to effect this result whenever the collecting shoes have cleared the ramp rails. It will be noticed that the studs, 39 and 40, and the contacts, 45 and 46, co-acting therewith, are so arranged that when the collecting shoe, A_2 , is raised the circuit between the stud, 39, and contacts, 45, is closed while that between studs, 40 and 46, is opened. When the collecting shoe, A_2 , is lowered the circuit between contacts, 45, and stud, 39, is opened while that between stud, 40, and contacts, 46, is closed.

As before explained, on the shoe, A_2 , being raised the circuit between stud, 39, and contacts, 45, is completed and the solenoid, A_R , energized. When the shoes leave the ramp rails and before the solenoid, A_R , is de-energized, the circuit is completed between the stud, 40, and the contacts, 46. Current thus passes from the positive pole of the dynamo along wires, 2^a , 2^b , to the wire, 60, thence across contacts, 49, and stud, 43.

From the right hand contact, 49, the current passes through lead, 10^a , and terminal, 10, to the solenoid, M, which it energizes breaking the lighting circuit at m' , to the "on ramp" signal and closing circuits at the contacts at m^9 , which illuminates the "off ramp" signal. The energization of the solenoid M, also places the lead, 2^a , in circuit with contacts, m^3 , m^4 , m^5 , m^6 , and m^7 , which are connected to contacts, $m\ s^3$, d^3 , r^3 , $s\ s^3$, and h^3 respectively, thus retaining any of the cores of the solenoids, M S, D R, S S and H which have been raised previously.

As the solenoids, H and R, were energized in passing over the ramp rails after the col-

- lecting shoes have dropped sufficiently to cause the solenoid, M, to be energized, current from the lead, 2^a, will pass to the solenoids, H and R, by way of contact, m⁷, lead, 5 m^c and contact h³, and contact, m⁵, lead m^b, and contact, r³, so that when the collecting shoes are lowered to their original position the signals "clear" and "fast road" will remain illuminated on the signal board.
- 10 The amount of current for holding the core of the solenoids in their energized position may be diminished by the insertion of suitable resistances, 83 or 84, as the power required to hold them in the energized position is less than that necessary to operate them. The above arrangement thus provides for the efficient utilization of the power.

Track circuits open.—Suppose for example that the track circuits remain open. 20 In this case the solenoid, A R, alone will be energized and no current will pass along the leads, 6^a and 8^a. Current from the lighting battery will pass along the leads, 3^a, 3^b and 3^c, contacts m s', lead, 56, contacts, h', and lead, 82, to the stop signal, R S, which will disclose the signal at its "danger" position. The solenoid, R, being deenergized, will cause a lighting circuit to be completed through leads, 3^a and 3^c, contacts, r', and lead, 81, which will disclose the route signal "slow road."

Repeater signal.

Track circuits closed.—In order to transmit a "repeater" signal to the locomotive the ramp rails are arranged as shown in Fig. 5, the switches, 32 and 33, being closed. The closure of circuits consequent on the shoes at the left hand side of the locomotive being raised, is effected in a similar manner to that described with regard to the "stop signal" so that the solenoids, R, and A R, are energized as previously. As the shoe, B₂, is also raised by the ramp rail, 30, a circuit is closed by the coöperation of the stud, 42, and the contacts, 48, so that current passes from the positive pole of the dynamo along leads, 2^a, 2^b, 2^c, thence by the lead, 11^a, through the terminal, 11, to contacts, b r², and energizes 40 the relay B R. The relays, A R and B R, are both energized in this case and as a result the contacts a r', and b r', are opened and a r³, a r⁴, a r⁵, b r³, b r⁴ and b r⁵, are closed. The current from the shoe, A₁, passes along the lead, 6^a, to the contacts, b r⁵, thence along leads, 61 and 62, to contacts, d³, around the solenoid D, and to the negative pole of the dynamo by the return wire, 1^a. Current from the dynamo also passes along the lead, 2^a, to the contacts b r⁴, thence through lead, 63, to contacts, a r⁴. From the contacts, a r⁴, the current passes along lead, 64, to contacts, m s², energizing coil, M S, and then returning by wire, 1^a. The solenoids, M S, and D, 65 are thus energized, opening the circuits

through contacts m s', m s², d', d² and d³, and closing the contacts, m s³, m s⁴, m s⁵ and d⁴, d⁵, d⁶. Lighting current from the storage battery is thus enabled to pass along leads, 3^a and 3^c, to contacts, m s⁵, thence by leads, 70 65, contacts, s s', leads, 66 and 67, to contacts, d³, and thence to signal, G. S. by wires, 68 and 58. The signal G. S. is thus used for the clear position of both the repeater and stop signals and in normal circumstances after 75 receiving it on the repeater ramp rails it will be maintained unaltered when passing over the stop signal ramp rails thereby avoiding multiplication of signals. The solenoid, R, being also energized the route signal "fast 80 road" is displayed.

Track circuits open.—If the track circuits remain open then it will be seen that only the circuits co-acting with the shoes, A₂ and B₂, are closed which results in the energization of the relays, A R, and B R, as above described. The only circuit completed by the energization of these relays is that from the lead 2^a which passes by way of contacts, b r⁴, and a r⁴, to energize the solenoid, M S. 90 The energization of this solenoid permits lighting current from the lead, 3^c, to pass by way of contacts, m s⁵, along lead, 65, to contacts, s s', thence by lead, 66, to contacts, d². The left hand contact, d², is connected 95 by a lead, 69, to the lamps of the repeater danger signal, Y R, the lamps being connected to the common lamp return, X. The "repeater danger" signal will thus be displayed as well as "slow road" on the route 100 indicator.

Distant signal.

In order to transmit distant signal indications to the locomotive an arrangement of 105 ramp rails as illustrated in Fig. 6 coöperates with the shoes on the locomotive.

Track circuits closed.—If the switches, 32 and 33, as illustrated in Fig. 6 are placed in the closed position, then when the shoes of 110 the locomotive encounter the ramp rails the following circuits will be completed. As there are six ramp rails in the arrangement all the shoes on the locomotive will be raised. The track circuit arrangements for the 115 shoes, A₁, A₂, and A₃, being the same as for the other signals as above described, the solenoids, R and A R, are energized as formerly.

The circuits which are operated on the 120 raising of the shoes, B₁, B₂ and B₃, are as follows: Current from the positive pole of the dynamo passes along leads, 2^a, 2^b, and by the coöperation of the contacts, 47, and the stud, 41, to the lead, 70. As the shoe, B₃, is raised by the rails, 31, current from the lead, 70, passes across the contacts, 50 and stud, 44, to lead, 9^a. The lead, 9^a, is connected through the terminal, 9, to the solenoid, S S, with the result that on raising 125

of the shoes, A_3 and B_3 , current from the lead, 2^a , energizes the solenoid and thereafter returns to the negative pole of the dynamo by the return wire, 1^a . The raising 5 of the shoe, B_2 , and the co-operation of the stud, 42, and contacts, 48, allows current to pass along the lead, 11, and energizes the relay, $B R$, as before. The raising of the shoe, B_3 , also allows current from the lead, 2^e , to 10 pass through the track circuit to the lead, 12^a , across contacts, p^2 , to the left hand contact, $a r^5$, and the right hand contact, $b r^5$. Owing to the energization of the solenoids, the contacts, $a r'$, and $b r'$, are opened and 15 contacts $a r^3$, $a r^4$, $a r^5$, and $b r^3$, $b r^4$, $b r^5$, are closed. Current from the lead, 2^a , energizes solenoid $M S$ as before, while the solenoid, D , is also energized by current from lead, 6^a , by way of contacts, $b r^5$ and from lead, 20 12^a , by way of contacts, $a r^5$, the currents combining and passing along leads, 61 and 62, to the solenoid.

The relays, $A R$ and $B R$, and the solenoids, R , $M S$, $S S$, D , are thus energized by 25 the contact of the shoes with the arrangement of ramp rails for the distant signal as shown in Fig. 6. The solenoids $M S$, $S S$, and D , being energized cause the contacts on their lower sides to be opened and the 30 contacts on their upper sides to be closed consequently lighting current from the lead, 3^b , passes through the contacts, $s s^4$, to the lead, 71, then by the lead, 72, to the contacts, $m s^4$. The current then passes through 35 the leads, 73, 74, and 75, to the contacts, d^e , and thence to the signal $G. D.$ by the lead, 76. The "clear" distant signal is thus displayed. The solenoid, R , being energized gives the route signal "fast road".

40 *Track circuits open.*—If the track circuits are open the relays, $A R$, $B R$, and the solenoids, $S S$ and $M S$, are energized, as these devices are operated by circuits independent of the track circuits and completed 45 upon the raising of the shoes by the ramp rails. Lighting current from the lead, 3^b , passes through contacts, $s s^4$, leads, 71, 72, contacts, $m s^4$, leads, 73 and 74, to the contacts, d' , and thence to the signal board by 50 the lead, 77. The current from the lead, 77, illuminates the lamps of the signal, $Y D$, and indicates the "danger" distant signal. The "slow road" indication will also be given.

55 *Simultaneous stop and distant signal indications.*—In order to transmit simultaneous stop and distant signals to the locomotive the arrangement of ramp rails illustrated in Fig. 7 is provided. In this case 60 three switches are provided with the circuits arranged as shown. The operation of the arrangement with these switches closed and open will now be described.

65 *Track circuits closed.*—The relay, $A R$, will be energized directly by the raising of

the shoes, A_1 , A_2 , and A_3 , while the solenoid, $S S$, will be energized directly by the raising of the shoes, A_3 and B_3 . A circuit will also be completed through the lead, 6^a , (when the relay $A R$ is energized) contacts, $a r^3$, leads, 53, 54, contacts, $b r'$ lead, 55, to energize the solenoid, H . A second circuit will also be completed through the lead, 12^a , contacts, $b r^5$, leads, 61, and 62, contacts, d^e , which energizes the solenoid, D . The solenoid R is energized by current passing from the rail, 31, through switch, 33^a , and rail, 27, to the shoe A_2 . The solenoids, H and D , and R , are thus energized.

The lighting circuits operated by the energization of the solenoids, H , D , and $S S$, are as follows:—Current from the lead, 3^b , passes to the contacts, $s s^4$, thence by the leads, 71 and 72, contacts, h^5 , leads 73, 74, 75, contacts, d^e , to the lamps of the signal $G. D.$ by the lead, 76. Current also passes along the leads, 3^b and 3^h , to contacts, $m s'$, and thence by leads, 56, 57, contacts, h^4 , to the lead, 58, which is connected to the lamps illuminating the "clear" stop signal, $G. S.$ Stop and distant "clear" signals as well as the route indication "fast road" will be displayed on the signal board when the track circuits are closed.

70 *Track circuits open.*—When all the track circuits are open it will be obvious that only the relay $A R$, and the solenoid $S S$, will be energized. Lighting current will then pass along the lead, 3^b , contacts, $m s'$, lead, 56, contacts, h' , lead, 82, to illuminate the 75 lamps behind the signal, $R S$, which gives the "danger" stop signal indication. No indication in this case is given as to the condition of the distant signal as if circuits were set for illuminating both types of signal with the stop signal at danger, and failure of the lamps illuminating the stop signal occurring a distant signal indication might be given which would cause the driver to proceed. If the switch, 32, is closed and the 80 switches, 35, and 33^a , are opened, Fig. 7, then the collecting shoe A_1 , will be connected in circuit with A_3 , when the collecting shoes traverse the ramp rails. As the shoe, A_2 , is lifted the relay, $A R$, is energized, 85 and current from the lead, 6^a , passing through the contacts, $a r^3$, and $b r'$, energizes the solenoid, H . As the shoes, A_3 and B_3 , are also lifted, the solenoid $S S$, will also be energized. The relay, $A R$, and the solenoids, $S S$, and H , are thus energized when 90 the switches, 33^a and 35, are open and the switch, 32, closed. Lighting current will thus pass from the lead, 3^b , and 3^h , through contacts, $m s'$, leads, 56 and 57, contacts h^4 , lead, 58, to the lamps of "clear" stop signal $G. S.$ Lighting current will also pass from lead, 3^b , to contacts, $s s^4$, leads, 71, 72, contacts, $m s^4$, leads 73, 74, contacts, d' , lead, 77, to the lamps illuminating the lamps of 95

"danger" distant signal Y. D. As the route control switch has not been closed the solenoid, R, is not energized and the route indication "slow road" will be displayed.

- 5 It will be understood that after the locomotive has passed over a set of ramp rails the solenoid, M, becomes energized before the collecting shoes have dropped to such an extent that the circuits actuating any of the 10 active solenoids, R, M S, H, D, and S S, have been broken. The active solenoids will thus have become energized by such of the leads, m b, m a, m e, m c and m d, as co-act therewith, before the current which initially 15 energized them has been cut off. In this manner the signals displayed on the locomotive passing over a set of ramp rails instead of being changed or extinguished after the ramp rails are passed, are retained until 20 the next set are encountered by the collecting shoes.

It will be observed that all the signal controlling solenoids are connected to the wire, 1^a, which leads to the negative pole 25 of the dynamo. The connection from this wire to the coil, P, thereafter passes through the coil, 85, of the auto-switch and is earthed. In the event of any of the operative circuits containing these signal controlling solenoids becoming earthed a shunt will 30 thus be formed through the coil, P, and the coil, 85. These coils are of low resistance and the circuit which contains them will be shunted across the solenoids, H and 35 D, when the track circuits are opened to give a danger signal, owing to the switches in their open position being earthed as shown in Figs. 4 to 7. This earth shunt assists the solenoid in falling to give a danger 40 signal when a set of ramps with the track circuits open are encountered if the signal previously displayed was a clear signal. Also in the event of considerable leakage 45 by earthing of the ramps taking place the current will be shunted first of all through the circuit containing the coil, P, and the resulting diminution of the current through the acting solenoid will result in the danger signal being given. If the leakage increase 50 the coil, P, will become energized, and break the circuit through the wires, 6^a or 12^a, leading by way of the relays, A R, and B R, to the solenoids, H and D. When the leakage becomes excessive the coil, 85, will 55 become sufficiently energized to trip the switch, 87, extinguish any active signals on the signal board, and close the circuit through the contact, 51, which will energize the circuit through the wire, 4^a, and 60 display the "out of action" signal.

The arrangement which I have above described is suitable for running tender first as well as funnel first. In the former case it will be evident that the shoes, B₁, B₂, and 65 B₃, will contact with the ramp rails, 26, 27,

and 28, while the shoes, A₁, A₂, and A₃, will contact with the ramp rails, 29, 30 and 31. Owing to the symmetry of the systems however the only change will be that instead of the relay, A R, being energized when the 70 ramp rails, 26 to 28, are encountered, the relay, B R, is energized.

It is advantageous to extend the contacts in the switches of the shoes controlling the signaling currents so that those paths which are complete when the shoes are raised remain complete until the shoe has fallen through rather more than half its travel. If at the same time the coil circuit for maintaining the signals in their operative position, which is opened when the shoes controlling the circuit are raised, is completed (as far as the shoes are concerned) just before the shoes have fallen to its mid-way position, there is a small portion of the stroke during which both circuits are complete in the case of the solenoids which are energized and the signal is maintained. Further instead of providing only one solenoid such as M, for controlling the currents for maintaining all the solenoids for the lighting circuits, several solenoids may be provided, the circuits for maintaining the signal in its operative condition being completed either mechanically 90 by the movement of the shoes or electrically by means of relays, or some of the circuit may be completed mechanically and the remainder electrically. The solenoids may be operated either from collecting shoes distinct from those coöperating with the track circuits or in conjunction with them as before described. Again in some cases the current for maintaining the solenoids, H and D, for example in their energized positions may be led from the dynamo through switches actuated by the raising of appropriate shoes.

If the solenoids for maintaining the signals in its operative position are sluggish in their action it may be necessary to make the incline at the end of the ramp rails very gradual; or the ramp rails, A₂ and B₂, operating the solenoid, M, may be dropped at a point somewhat in advance of the other ramp rails to a level which retains the shoe at its mid-way position for a short distance in order to give the solenoid, M, time to rise and complete the circuits for maintaining the signals in their operative position before the signaling currents are lost.

In the example which I have described it will be seen that the same ramp rails act to mechanically close circuits on the locomotive as well as to electrically complete circuits partly on the track and partly on the locomotive. In some cases however these functions may be performed by separate ramp rails.

In certain cases, such as the automatic 130

block system described in the British patent specification No. 18,996 of 1908, a current is sometimes required to operate coils in the track apparatus from the dynamo in the engine, without a signal being given thereon. In such a case, the apparatus above described may be modified by placing any required number of rails to engage with the shoes, provided any combination of rails is not used which would interfere with the signal board indication by operating the shoes controlling the solenoid M or SS.

The necessary connection to the dynamo is made in the engine by an appropriate selection of shoes, one of which is connected to the dynamo, while the corresponding track rail is joined to the coil in the track apparatus. The return circuit may be earthed or a special rail and shoe may be used for this.

It will be evident that by means of my invention an efficient and reliable signaling system of wide application and adaptability is provided, one of the important features being that danger signals are automatically given whenever the collecting shoes contact with the ramp rails and are thus independent of any action on the part of the signalmans. Further as the solenoids are gravity controlled and the danger signal is operated by them in their lowered position any failure on the part of the active signaling apparatus always tends to give a safer signal than that for which the circuits are set. Also in the event of substantial leakage taking place the danger signal is automatically given, by the deenergizing of the active coils, or the opening of the circuit through the relay contacts controlling the solenoids, H and D. When the leakage is excessive the dynamo auto-switch, 37, is opened and the "out of action" signal displayed.

The possibility of giving wrong signals is largely reduced by my invention while the lengths of the ramp rails may be materially reduced.

I wish it to be understood that the example which I have hereinbefore described is simply to be regarded as typical and not in any way limiting my invention thereto as it will be evident that many modifications may be made without departing beyond the scope of my invention.

Having now described my invention what I claim as new and desire to secure by Letters Patent is:—

1. In an electrical cab signaling system a plurality of contact devices on the cab, together with groups of signal controlling bars along the track, the bars of each group co-acting simultaneously with corresponding contact devices, said groups differing in accordance with the type of signal desired to be displayed, substantially as described.

2. In an electrical cab signaling system, a plurality of contact devices on the cab, groups of signal controlling bars along the track, the bars of each group co-acting simultaneously with corresponding contact devices, said groups differing in accordance with the type of signal desired to be displayed, means for giving signals automatically on contact of said devices and bars, together with means to control said bars for giving desired signals at will, substantially as described.

3. In an electric cab signaling system, a plurality of contact devices in the cab, groups of signal controlling bars along the track, the bars of each group co-acting simultaneously with corresponding contact devices, said groups differing in accordance with the type of signal desired to be displayed, circuits interconnecting said signal controlling bars, switches controlling said circuits, together with means for displaying a certain signal in the open position of said switches and a certain other signal in the closed position of said switches, substantially as described.

4. In an electrical cab signaling system, a plurality of contact devices on the cab, groups of signal controlling bars along the track, the bars of each group co-acting simultaneously with corresponding contact devices, said groups differing in accordance with the type of signal to be displayed, together with means for maintaining the displayed signals between successive groups of bars, substantially as described.

5. In an electrical cab signaling system, a plurality of contact devices on the cab, groups of signal controlling bars along the track, the bars of each group co-acting simultaneously with corresponding contact devices, said groups differing in accordance with the type of signal to be displayed, a plurality of signals in the locomotive cab, solenoids movable into an operative position to actuate same on contact of said devices and said bars, together with a single solenoid for retaining any of said signals' solenoids in the operative position between successive groups of bars, substantially as described.

6. In an electrical cab signaling system, a plurality of vertically movable contact devices on the cab, groups of signal controlling bars along the track, the bars of each group co-acting simultaneously with corresponding contact devices, signal-operating circuits on said cab adapted to be closed on contact of said devices with said bars and signal-maintaining circuits associated with said signal-operating circuits and adapted to be closed on said devices leaving said bars, substantially as described.

7. In an electrical cab signaling system, a

plurality of resiliently mounted contact devices on the cab, groups of signal controlling bars along the track, the bars of each group co-acting simultaneously with corresponding 5 contact devices, signal-operating circuits on said cab adapted to be closed on contact of said devices with said bars and signal-maintaining circuits associated with said signal-operating circuits and adapted to be closed 10 on said devices leaving a group of bars and to be opened on said devices contacting with a succeeding group of bars, substantially as described.

8. In an electrical cab signaling system, a 15 plurality of contact devices on the cab, a plurality of groups of signal controlling bars along the track, the bars of each group co-acting simultaneously with corresponding contact devices, means for closing certain 20 circuits in said cab on contact of said devices and said bars, signal-operating circuits on said cab adapted to be closed on contact of said devices with said bars and to be opened on said devices leaving said bars, 25 and signal-maintaining circuits associated with said signal-operating circuits and adapted to be closed on said devices leaving said bars, the closure of said signal-maintaining circuits being effected prior to the 30 opening of said second mentioned circuits, substantially as described.

9. In an electrical cab signaling system, a plurality of signals in the cab, a plurality of solenoids for operating same, a plurality 35 of signal controlling bars along the track, means co-acting simultaneously with said bars for energizing certain of said solenoids to display a signal, means also co-acting with the same bars to maintain said energized 40 solenoids in their operative position between successive groups of bars, substantially as described.

10. In an electrical cab signaling system, a plurality of contact devices on the cab, 45 groups of signal controlling bars along the track, the bars of each group co-acting simultaneously with corresponding contact devices, means co-acting with the same group of bars for displaying a signal corresponding to the grouping of said bars, 50 and maintaining said displayed signal be-

tween successive groups of bars, substantially as described.

11. In an electric cab signaling system, a plurality of signal controlling bars along 55 the track grouped to correspond to the type of signal such as home, distant and repeater signals, a plurality of signals in said cab to correspond to various groups of said bars, circuits interconnecting said bars, switches 60 controlling said circuits, means for displaying a danger signal of the type corresponding to the grouping of said bars in the open position of said switches, and a clear signal in the closed position of said switches. 65

12. In an electrical cab signaling system, a plurality of contact devices on the cab, groups of signal controlling bars along the track, the bars of each group co-acting simultaneously with corresponding contact 70 devices, a plurality of signals, a plurality of circuits controlling said signals, and operable on contact of said contact devices and bars, a switch for controlling said circuits, means for automatically operating a danger 75 signal on a certain amount of leakage taking place, together with means for opening said switch when leakage is greater than said certain amount, substantially as described.

80 13. In an electrical cab signaling system, a plurality of contact devices on the cab, groups of signal controlling bars along the track, the bars of each group co-acting simultaneously with corresponding contact 85 devices, a plurality of clear signals, a plurality of danger signals, means including electro-magnetic devices for displaying a clear type of signal when said electro-magnetic devices are energized together with 90 means for displaying a danger type of signal when said electro-magnetic devices are in a deenergized position, substantially as described.

95 In testimony whereof I have signed my name to this specification in the presence of two subscribing witnesses.

HERBERT BROWN.
